(57) **CLAIM**

The ornamental design for a vehicular radius arm, as shown and described.

DESCRIPTION

FIG. 1 is a front perspective view of the vehicular radius arm of the present invention showing our new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a left end view thereof; and,

FIG. 7 is a right end view thereof.
